(57) **ABSTRACT**

A new *Osteospermum* plant particularly distinguished by lavender flower color, with a white pattern under cold stimulation which otherwise is not visible or only slightly visible, with an upright habit and good branching, is disclosed.

1 Drawing Sheet

1

Genus and species: *Osteospermum ecklonis* Norl.
Variety denomination: 'KLEOE23403'.

BACKGROUND OF THE NEW PLANT

The present invention comprises a new and distinct variety of *Osteospermum*, botanically known as *Osteospermum ecklonis* Norl., and hereinafter referred to by the variety name 'KLEOE23403'. 'KLEOE23403' originated from a cross-pollination conducted in summer 2015 in Nairobi, Kenya between the proprietary female *Osteospermum* variety 'KLEOE14226' (unpatented) and the proprietary male *Osteospermum* variety 'OE-2013-0357' (unpatented).

The seeds from the cross were collected and sown in Stuttgart, Germany in January 2016 and the plants were grown for evaluation. An individual plant designated 'KLEOE23403' was selected in April to May 2016 in Stuttgart, Germany. In June 2016 'KLEOE23403' was first vegetatively propagated by vegetative terminal cuttings in Stuttgart, Germany. 'KLEOE23403' was found to reproduce true to type in successive generations of asexual propagation via vegetative cuttings.

SUMMARY

The following are the most outstanding and distinguishing characteristics of this new variety when grown under normal horticultural practices in Stuttgart, Germany.

1. Lavender flowers, with a white pattern under cold stimulation which otherwise is not visible or only slightly visible;
2. Upright habit; and
3. Good branching.

DESCRIPTION OF THE PHOTOGRAPH

This new *Osteospermum* plant is illustrated by the accompanying photograph which shows a close-up of the foliage,

2

buds, and mature flower. The photograph is of a 12-week-old plant grown outdoors in Stuttgart, Germany in May 2022. The colors shown are as true as can be reasonably obtained by conventional photographic procedures.

DESCRIPTION OF THE NEW VARIETY

The following detailed descriptions set forth the distinctive characteristics of 'KLEOE23403'. The data which define these characteristics were collected in Stuttgart Germany in May 2024 on plants potted in October 2023. References are to The R.H.S. Colour Chart of The Royal Horticultural Society of London (R.H.S.), 5th edition (2007). Classification:

Family.—Asteraceae.
Botanical.—*Osteospermum ecklonis* Norl.
Common.—*Osteospermum*.
Designation.—'KLEOE23403'.

Parentage:
Female parent.—The proprietary female *Osteospermum* variety 'KLEOE14226' (unpatented).

Male parent.—The proprietary male *Osteospermum* variety 'OE-2013-0357' (unpatented).

Plant:
Form and habit.—Herbaceous perennial but usually cultivated as an annual; not frost resistant.

Growth habit.—Upright.

Branching habit.—Normal.

Height (from top of soil, including inflorescence).—16.0 cm.

Width (including inflorescences).—17.0 cm.

Propagation.—Vegetative cuttings.

Time to produce a finished flowering plant.—10 to 17 weeks.

COMPARISON WITH PARENTAL LINES AND KNOWN VARIETY

'KLEOE23403' is a distinct variety of *Osteospermum* and is distinguished from its parents as described in Table 1.

TABLE 1

Comparison with Parental Lines				
Characteristic	'KLEOE23403'	Female Parent	Male Parent	
55 Flower color	Lavender, with white pattern under cold stimulation which otherwise is not visible or only slightly	Pink	Purple	
60				

‘KLEOE23403’ is most similar to the commercial *Osteospermum* variety ‘KLEOE14235’ (U.S. Plant Pat. No. 27,268). Differences between the varieties are described in Table 2.

TABLE 2

Comparison with Similar Variety		
Characteristic	'KLEOE23403'	'KLEOE14235'
Branching	Better than 'KLEOE14235'	Medium
Earliness	Early	Very early

I claim:

1. A new and distinct variety of *Osteospermum* plant
 designated 'KLEOE23403' as illustrated and described
 herein.
